(57) CLAIM

The ornamental design for a case for a watch, as shown and described.

DESCRIPTION

FIG. 1 is a front perspective view of a case for a watch showing our design;

FIG. 2 is a top view thereof;

FIG. 3 is a bottom view thereof;

FIG. 4 is an elevational view of the right side of the case for a watch;

FIG. 5 is an elevational view of the left side opposite to that of FIG. 4;

FIG. 6 is an elevational view of one side of the case for a watch comprising the seat for a watch strap; and,

FIG. 7 is an elevational view of the side opposite to that of FIG. 6.
